UNITED STATES PATENT OFFICE.

JOHN H. KINSLEY, OF CLINTON, MASSACHUSETTS.

TELEGRAPH SOUNDER.

Application filed March 27, 1920. Serial No. 369,299.

To all whom it may concern:

Be it known that I, JOHN H. KINSLEY, a citizen of the United States, residing at Clinton, in the county of Worcester and State of Massachusetts, have invented a new and useful Telegraph Sounder, of which the following is a specification.

This invention relates to a telegraph sounder of the usual lever type. Such sounders are commonly provided with an adjusting screw and lock nut, by which the movement of the armature lever may be adjusted and maintained.

In large offices, an operator may have a considerable number of different sounders, on any one of which a message may be received. It is desirable under these conditions to be able to reduce or soften the sound from all of the sounders except the one on which the message is received, in order that the message may be accurately read. This has been accomplished in several different ways, as by moving the magnets from operative position, locking the armature lever, or by using a relay and local batteries when a loud tone is desired.

The first described methods are objectionable as the operator may easily forget to restore the disabled sounders to operative condition after receiving his message and in this case he will thereafter miss all calls made on the disabled sounders. The method of using relays and local batteries is expensive and considerably complicates the equipment of each office.

It is the object of my invention to provide improved means for varying the tone of the instrument without disturbing the regular adjustment thereof. In the preferred form, my invention permits the sounder to operate with a subdued tone at all times except when a message is to be received, when a simple adjustment of the sounder causes the same to deliver the message in a loud and clear tone.

My invention further relates to certain constructions and arrangements of parts which will be hereinafter described and more particularly pointed out in the appended claims.

A preferred form of my invention is shown in the drawings, in which—

Fig. 1 is a side elevation of a common form of telegraph sounder with my invention applied thereto;

Fig. 2 is a plan view thereof;

Fig. 3 is a detail side elevation partly in section;

Fig. 4 is a sectional bottom view taken along the line 4—4 in Fig. 1; and

Fig. 5 is a perspective view of a part to be described.

Referring to the drawings, I have shown a usual form of instrument, comprising a frame 10, magnets 11, an armature 12, and an armature lever 13 mounted upon a fixed pivot 14. A spring 15 normally holds the lever 13 against the end of an adjusting screw 15^a which is held in adjusted position in the frame 10 by a lock nut 16. A stud or pin 17 (Fig. 3) commonly extends downward from the lever 13 in position to engage an arm or projection 18 of the frame 10. The sound of the instrument is produced by engagement of the stud 17 with the projection 18 and the loudness of the sound depends largely upon the travel of the lever between the adjusting screw 15^a and the projection 18. Other conditions remaining unchanged, increased travel produces a louder tone. All of the parts thus far described are or may be of the usual commercial construction.

My invention consists in a device for limiting the travel of the lever 13 independently of the adjusting screw 15, and as shown in the drawings, comprises a disc 20 held against the under side of the lever 13 and loosely centered by the stud 17. The disc 20 is held in position by a spring 21 embracing the lever 13 and holding the disc firmly against the under side of the lever. The spring may be conveniently held in position by the screw 19 which also locates the armature 12.

Projections 22 and 23 are provided on the under side of the disc 20 which engage the sides of the arm or projection 18 of the frame 10 and limit angular movement of the disc in both directions. Between the projections 22 and 23 additional projections 24 and 25 are provided, so positioned that the projection 25 lies over the part 18 when the stop 22 is against the side of said part and the projection 24 is above the part 18 when the projection 23 is against the side thereof.

After the disc has been placed in position, the screw 15^a is adjusted so that the sounder will deliver a loud tone when the shorter projection 24 is above the part 18. This tone may be produced by engagement

of the projection 24 with the part 18 or by engagement of the regular sounding stud 17 with said part. The projection 25 is slightly longer than the projection 24 and reduces the travel of the lever 13 when positioned above the part 18, the remaining motion permitting the sounder to deliver only a soft or subdued tone.

Having described the construction of my improvement, the operation thereof will be apparent. All of the sounders are normally set with the projections 25 above the parts 18, so that they deliver reduced sounds and they are allowed to remain in this position until the operator hears his call on one of the sounders. He then turns the disc 20 of that particular sounder so that its projection 24 is above the part 18 and this sounder then delivers a loud clear tone. After the message has been received, the disc should be restored to its initial position.

If the stud 17 engages the arm 18 to deliver the loud note, the projection 24 may be omitted. It will also be evident that the device may be easily reversed by placing the disc or some similar element upon the part 18 instead of upon the lever 13.

Having thus described my invention, it will be evident that other changes and modifications may be made in my invention by those skilled in the art within the spirit and scope thereof as set forth in the claims, and I do not wish to be otherwise limited to the details herein disclosed, but what I claim is:

1. In a telegraph sounder, a frame, an armature, a lever pivoted to said frame, adjusting means effective to determine the normal range of movement of said lever, and an additional adjusting device effective to determine for said lever a relatively long or a relatively short stroke independent of said normal adjusting means, said device

having two separate engaging portions and 45 being selectively movable to either one of two definite operative positions in each of which one engaging portion only is effective to determine the length of stroke.

2. In a telegraph sounder, a frame, an 50 armature, a lever pivoted to said frame, means to determine the normal range of movement of said lever, and a disc seated against said lever, effective by movement on its seat to different selected angular positions to change such range of movement independently of said means.

3. In a telegraph sounder, a frame, an 55 armature, a lever pivoted to said frame, means to adjust the range of movement of 60 said lever, a manually movable disc seated against said lever, effective by angular adjustment on its seat to temporarily change such range of movement independently of 65 said means, and a device to hold said disc in adjusted position.

4. In a telegraph sounder, a frame, an 70 armature, a lever pivoted to said frame, means to adjust the range of movement of 75 said lever, a disc mounted on said lever, effective to temporarily decrease such range of movement independently of said means, and a spring mounted on said lever and frictionally engaging said disc to prevent displacement thereof.

5. In a telegraph sounder, a frame, an 80 armature, a lever pivoted to said frame, means to adjust the range of movement of 85 said lever, and a disc adjacent said lever having projections of different lengths at different points on its periphery, different projections engaging said frame in different positions of said disc and varying the range of movement of said lever.

In testimony whereof I have hereunto 85 affixed my signature.

JOHN H. KINSLEY.
